(57) **CLAIM**

The ornamental design for a golf swing trainer, as shown and described.

DESCRIPTION

FIG. 1 is a perspective view of the golf swing trainer showing my new design;

FIG. 2 is a front view thereof;

FIG. 3 is a rear view thereof;

FIG. 4 is a left side view thereof;

FIG. 5 is a right side view thereof; and,

FIG. 6 is a top side view thereof.

The broken lines showing the belt and portions of the buckle are for illustrative purposes only and form no part of the claimed design.

1 Claim, 2 Drawing Sheets

FIG. 2

FIG. 3

FIG. 5
